the cross section of the melting channel is gradually widened to the point where the greatest heat accumulation takes place. The channel cross sectional area will be widest at this point and again gradually reduces towards the other mouth of the melting channel. The latter construction is illustrated in Fig. 2, the individual parts correspond to those shown in Fig. 1 and are consequently designated by similar reference characters.

In the case of furnaces, which utilize the repulsion effect of the primary coil (Figs. 3 and 4), the melting channel *c* is very often made of helical shape or crossed in order to obtain a uni-directional flow in the melting channels. In order to attain this, the repulsion effect ought to be made very strong, so that it overcomes the inwardly and outwardly directed flow (see Fig. 1) caused by the "pinch-effect". A strong repulsion effect of the coil results, however, in a bad output coefficient. Therefore, one has hitherto generally been satisfied with a lower repulsion effect, which causes a one-sided flow, that is superimposed on the outwardly and inwardly directed flow. Consequently, the point where a heat accumulation takes place is displaced towards the side of the channel arm on which the outwardly directed flow caused by the "pinch-effect" and the flow caused by the repulsion effect counteract each other. The widening *h* of the channel cross section must therefore be arranged at the same point. This point is no longer situated, as mentioned above, equidistant from the two channel mouths but shifted towards one of the channel mouths. The reference characters otherwise correspond to those of Figs. 1 or 2.

The invention has been described in connection with two forms of example. According to the construction of the melting channel and to the object to be attained it can also be employed in another form of construction. It can likewise be employed appropriately when, for example, the mouths of the melting channel have different cross sectional areas, for instance *g* and *f* according to Fig. 3 and Fig. 4. Particularly it is immaterial what relative position the melting channels occupy with respect to the melting bath, whether they are vertical, horizontal or

50

inclined, and what cross sectional shape they have.

I claim:—

1. An induction smelting furnace, comprising melting channels which form the secondary winding of a transformer, the cross sectional area of the melting channels being widened upon the whole length of the channel commencing from the nominal cross sectional area of the one channel arm and again narrowing to the nominal cross sectional area of the other channel arm. 80

2. An induction electric furnace of the type having a pool for molten metal and walls forming a single submerged channel which forms the secondary of a transformer, in which the cross sectional area of the channel is widened intermediate between the extremities of the channel at the point where excessive heating would otherwise develop. 90

3. An electric induction furnace of the type 95 having a pool for molten metal and walls forming a submerged channel which forms the secondary of a transformer, in which the cross sectional area of the channel is progressively and gradually widened and then progressively and 100 gradually narrowed from a point near one extremity to a point near the other extremity of the channel, the widened and narrowed portions having progressively curved contours.

4. An electric induction furnace of the type 105 having a pool for molten metal and walls forming a single depending submerged channel below the pool, in which the channel is of horseshoe contour and is continuously and progressively enlarged in cross section from points on either side 110 of the middle point toward the middle point, the enlarged portion having a progressively curved contour.

5. An electric induction furnace of the type 115 having a pool for molten metal and walls forming a single submerged channel, which increases in cross section from one end to the other, in communication with the pool, in which the channel cross section on the side of the channel nearest the largest end of the channel and at the 120 point at which the channel tends to overheat is enlarged with respect to the immediately adjoining channel cross sections.

HEINZ ILBERG.
